P.C.; Natu J. Patel(57) CLAIM

The ornamental design for a hexagonal hookah bowl, as shown and described.

DESCRIPTION

FIG. 1 is a perspective view of a hexagonal hookah bowl according to an embodiment of the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in FIG. 7 depict unclaimed subject matter and form no part of the claim.
